(57) **CLAIM**

We claim the ornamental design for a garment, as shown and described.

DESCRIPTION

FIG. 1 is a front view of a garment in a laid-flat configuration, according to the present design;

FIG. 2 is a front view of the garment in an as-worn configuration, according to the present design;

FIG. 3 is a front view of the garment in a top-closed configuration, according to the present design; and,

FIG. 4 is a front view of the garment in a top-closed and bottom-closed configuration, according to the present design.

The even-length broken lines showing the remainder of the garment and portions of the human figure illustrating the design in the as-worn configuration form no part of the claimed design.

The dot-dash broken lines are boundary lines that show that the claimed design extends to the boundary line, but does not include the boundary line.
